UNITED STATES PATENT OFFICE.

CHARLES ALGERNON PARSONS, STANLEY SMITH COOK, AND LOUIS MORTIMER DOUGLAS, OF NEWCASTLE-UPON-TYNE, ENGLAND; SAID COOK AND SAID DOUGLAS ASSIGNORS TO SAID PARSONS.

LUBRICATING SYSTEM.

Application filed September 21, 1921. Serial No. 502,199.

To all whom it may concern:

Be it known that we, CHARLES ALGERNON PARSONS, STANLEY SMITH COOK, and LOUIS MORTIMER DOUGLAS, all subjects of the King of Great Britain and Ireland, and residing at Heaton Works, Newcastle-upon-Tyne, in the county of Northumberland, England, have invented certain new and useful Improvements in Lubricating Systems, of

10 which the following is a specification.

The present invention relates to systems such, for example, as those described in British patent application No. 18024 of 1919, in which a common pump is employed to 15 pump oil through two or more paths. In such installations where oil coolers are arranged in parallel in different paths the coolers are so designed that in addition to reducing the temperature of the oil by the 20 desired amount they oppose such relative resistance to the flow of the oil as to obtain the proper relation between the quantities of oil passing through the respective coolers, that is to say, with the required pressures at 25 their outlets.

It has been found in practice, however, that through various causes these relative quantities are not as designed or required; and the resistances to flow through the coolers are liable to vary owing to variation in 30 the quality and condition of the oil, or, most important of all, owing to choking.

The object of the present invention is to ensure that the relation between the quantities passing through the two coolers will 35 be automatically maintained irrespective of the resistances of the coolers.

The invention consists in the employment in the oil circulating system of a piston valve 40 which is responsive to the pressure of the oil in the discharge from each cooler and is so actuated that when the pressure in the discharge from one cooler falls below the pressure in the discharge from the other cooler, 45 the supply in the latter cooler is restricted, while the supply to the former is increased.

The invention further consists in constructing the valve in such a manner that when the supply to one cooler has been restricted to a predetermined extent, any further movement causing further restriction of this supply will cause the other cooler to be by-passed, so that in the event of com-

plete or very considerable choking of either or both coolers, either or both of them will 55 be automatically by-passed and a proper quantity of oil supplied to the system.

The invention further consists in the improved means for controlling the flow of oil in lubricating systems hereinafter described. 60

Referring to the accompanying drawings:—

Figure 1 is a longitudinal section of the valve indicating diagrammatically the pipe connections to the coolers. 65

Figure 2 illustrates a modified form of valve.

Figure 3 is a fragmentary cross-section on the line A—A of Figure 2.

In carrying the invention into effect according to the example shown in Figure 1, in which a common pump delivers oil to two different systems through two coolers 1 and 2 in parallel, there is provided a valve comprising two pistons 3 and 4 of the same diameter connected by a stem 5, which valve can slide freely in a cylindrical casing 6. Oil from the pump is admitted by an inlet 7 to the central portion of the casing between the pistons 3 and 4 and passed to the coolers 80 through apertures 8 and 9 in the central portion of the casing. One aperture 8 or set of apertures is partially covered by the left hand piston 3 and leads to the cooler 1, while the other aperture 9 or set of apertures is 85 partially covered by the right hand piston 4 and leads to the other cooler 2. The left hand end of the valve casing is connected by a pipe 10 to the oil outlet from cooler 1, so that the outer end of the piston 3 is subjected 90 to the pressure in the system supplied through cooler 1, and, similarly, the right hand end of the valve casing is connected by a pipe 11 to the oil outlet from cooler 2. 95

The pressure of the oil between the pistons has no influence on the movement of the valve because the pistons are of the same area, but difference in the pressures acting on its outer ends, that is, difference in the pressures at the cooler outlets, causes the valve 100 to move towards the low pressure end. If the quantity of oil received by one system, say, that supplied through cooler 1, is defective, the pressure at the outlet of this cooler will fall and the higher pressure in 105 the outlet from cooler 2 will move the valve

to the left. The effect of this movement will be that the extent to which the piston 3 covers the aperture 8 leading to cooler 1 will be reduced and the open area through 5 the aperture thereby increased, while the extent to which the piston 4 covers the aperture 9 leading to cooler 2 will be increased, thereby reducing the open area. In consequence, the proportion of the total quantity 10 passing through cooler 1 will be increased and the variation will proceed until the outlet pressures from the two coolers are again equal. A defective supply through the cooler 2 would, of course, be rectified by the 15 valve moving in the reverse direction.

The apertures 8 and 9 may be made of any shape but are preferably of such form as to give a large movement to the valve and of such area that the pressure drop 20 across them is small when the valve is in the normal position.

The pistons are provided with by-pass apertures 14 and 15 leading from the central space between the pistons through the 25 cylindrical surfaces of the pistons. Each by-pass aperture is normally covered by the cylinder casing but is so disposed in relation to a recess 16 or 17 in the cylinder casing that when the inlet aperture to one cooler 30 has been restricted to a predetermined extent by one piston, the by-pass aperture in the other piston is over the recess which communicates with the outlet from the other cooler whereby the latter cooler is by-passed. 35 The movement of the valve in either direction is preferably limited by stops 18 so disposed that when the piston reaches them the by-pass aperture is sufficiently uncovered to pass the total quantity required for the 40 system whose cooler has been choked.

If desired a light spring or springs may be provided to assist in bringing the valve to the normal position and to prevent jerkiness in action.

45 In the event of obstruction occurring in both coolers simultaneously, it would not be possible by means merely of the apertures 14 and 15 to by-pass both coolers, and hence the supply of oil to one of the lubricating systems might fail. In order to meet such an eventuality the pistons are arranged to be movable on the spindle 5, the normal distance between them being determined by 50 flanges 30 and 31 formed on the spindle 5.

55 In the ordinary working of the apparatus, the pistons are maintained in contact with these flanges by springs 32, 33, which are compressed by nuts 34 and 35 and washers 36, 37 fitted on the outer end of the spindle 5. In the event of both coolers becoming 60 simultaneously choked or abnormally obstructed, the pressure at both ends of the cylinder 6 will be reduced, with the result that one or both pistons will slide along the spindle 5 against the action of the

70 springs 32 and 33, thus permitting oil simultaneously to flow through the apertures 14 and 15, ensuring a simultaneous supply to both lubricating systems, both coolers being by-passed.

75 It will be seen that the springs 32 and 33 might be replaced by a single tension spring, spaced between the pistons and connected to both of them. Further, it is possible to dispense entirely with the spindle 5, the spring acting as the sole connection between the pistons and being of sufficient strength to ensure that under normal conditions supply through the apertures 14 and 15 will not occur simultaneously.

80 In the modification illustrated in Figures 2 and 3, annular spaces 38 and 39 are provided between the pistons and the spindle 5, so that immediately either piston is forced out of contact with its corresponding flange 85 30 or 31, the supply of oil occurs to one of the by-passes 10 or 11 through the annular space and an aperture 40 or 41 leading from it to the space at the outer end of the corresponding piston.

90 It will be seen that the invention is also applicable to installations in which the resistance to flow through one system is very small in relation to that through the other system, as, for instance, when a cooler is provided in one of the paths only. In such cases the valve will automatically maintain such resistance to flow through the system without a cooler as to maintain equal oil pressures in the two systems supplied.

95 The control valve may be designed in several ways to give different discharge pressures. For instance, one of the piston ends may be stepped and the annular spaces between the steps connected to atmosphere, or the difference in pressure may be obtained by causing a spring of sufficient strength to act on one end of the valve or the valve may be placed vertically and made of sufficient weight to cause the difference in pressure required.

100 Having now described our invention, what we claim as new and desire to secure by Letters Patent is:—

115 1. A distributing valve comprising in combination a casing, two pistons fitting within said casing, said pistons being mounted on a common spindle so as to be capable of sliding along said spindle, and yieldable means tending to force said pistons together.

120 2. A distributing valve comprising in combination a casing, two pistons fitting within said casing, said pistons being mounted on a common spindle so as to be capable of sliding along said spindle, yieldable means tending to force said pistons together and flanges on said spindle to limit the inward motion of said pistons.

125 3. A distributing valve comprising in

combination a casing, two pistons fitting within said casing, said pistons being mounted on a common spindle so as to be capable of sliding along said spindle, yieldable means tending to force said pistons together, by-passes between said pistons and said spindle and flanges on said spindle to

limit the inward motion of said pistons and to close said by-passes.

In testimony whereof we have signed our names to this specification.

CHARLES ALGERNON PARSONS.

STANLEY SMITH COOK.

LOUIS MORTIMER DOUGLAS.
